UNITED STATES PATENT OFFICE

165,720

WARNING SIGNAL

Maurice C. Pierce, Chicago, Ill.

Application July 13, 1951, Serial No. 15,855

Term of patent 14 years

(Cl. D72—1)

To all whom it may concern:

Be it known that I, Maurice C. Pierce, a citizen of the United States, residing in Chicago, in the county of Cook and State of Illinois, have invented a new, original, and ornamental Design for a Warning Signal, of which the following is a specification, reference being had to the accompanying drawing, forming part thereof, in which

Fig. 1 is a front elevation view of a warning signal, showing my new design; and

Fig. 2 is a rear elevational view thereof, the dominant features of my design are shown in solid lines in the drawing.

I claim:

The ornamental design for a warning signal, as shown and described.

MAURICE C. PIERCE.
